UNITED STATES PATENT OFFICE.

FRANCIS SCHUMANN, OF TRENTON, NEW JERSEY, ASSIGNOR OF ONE-HALF
TO W. D. HAVEN, OF SAME PLACE.

STEAM-VALVE.

SPECIFICATION forming part of Letters Patent No. 339,814, dated April 13, 1886.

Application filed October 29, 1885. Serial No. 181,295. (No model.)

To all whom it may concern:

Be it known that I, FRANCIS SCHUMANN, a citizen of the United States, residing at Trenton, in the county of Mercer and State of New Jersey, have invented certain new and useful Improvements in Steam-Valves; and I do declare the following to be a full, clear, and exact description of the invention, such as will enable others skilled in the art to which it app-
10 pertains to make and use the same.

My invention relates, first, to certain im-
provements in the construction and relative
arrangement of a rotating and reciprocating
steam-valve and the surrounding casing or
15 steam-chest.

By the means which I have devised I am
able to use a single valve and a single rotating
device for both ends of the cylinder and at the
same time to effect the cutting off of the steam
20 entirely by the rotation of the valve. This
results in simplicity of mechanism and a cer-
tain and easily-regulated "cut-off" which is un-
affected by the longitudinal position or recip-
rocation of the valve.

25 My invention relates, secondly, to an im-
proved means for rotating and reciprocating
a valve to which such motions are necessary.
It is desirable that the cut-off by the rotation
of the valve should not be so gradual as to
30 produce what is termed "wire-drawing" the
steam, but that the port should be kept well
open till the time for cutting off approaches,
and that then the rotation of the valve should
35 be so accelerated as to effect the cut-off with
some degree of suddenness.

My invention can best be understood by
reference to the accompanying drawings, in
which I have shown means for carrying it into
effect.

40 In said drawings, Figure 1 is a side eleva-
tion, partly broken away, of a steam-cylinder,
steam-chest, valve, and operating mechanism
embodying my invention. Fig. 2 is a cross-
section of the valve and steam-chest or valve-
45 casing on the line 2 2. Fig. 3 is an end eleva-
tion of a part of the valve-operating mechan-
ism upon a larger scale.

A indicates the steam-cylinder, and B the
valve-casing or steam-chest. The latter is
50 cylindrical, receives the live steam through
an opening, b, communicates with the cylinder-

der at or near each end through ports a',
and communicates with the exhaust-ducts CC,
also at each end of the cylinder. A single
cylindrical valve fits in the case B, in which
55 it is reciprocated and oscillated by a valve-
stem, D, and opens and closes both the steam
and the exhaust ports at each end of the cyl-
inder. The valve is arranged to regulate the
admission of the live steam into the cylinder,
60 and particularly to perform the cutting off of
the steam-supply from the cylinder entirely
by its movement of rotation and independ-
ently of its reciprocation. The reciprocation
of the valve effects the opening and closing of
65 the exhaust-ports.

If the live steam in passing through the
valve and into the cylinder took such course
as to be materially affected in quantity by the
reciprocation of the valve, a regulation of the
70 rotation alone of the valve would not with
certainty regulate the speed of the engine;
but under the arrangement shown this latter
result is attained by connecting a speed-regu-
lator with those devices alone which cause the
75 rotation of the valve, since the cut-off is gov-
erned by the rotation alone. This latter end
is effected by admitting the live steam freely
and constantly to the interior of the valve,
and thence passing it periodically directly to
80 the interior of the cylinder by the registering
of the valve-ports, through the rotation or os-
cillation of the valve, with the cylinder-ports.

That portion of the valve which effects the
covering and closing of the cylinder-ports is
85 indicated at D' D'', consisting in the construc-
tion shown of two hollow cylinders secured to
the valve-stem through the medium of webs
d' and hubs d''. These cylinders are provided
90 with ports d' d'', adapted to register with the
ports a' a'', as above described. The ports d' at
one end of the valve are situated relative to
the ports d'' at the other end in a well-known
manner—that is to say, so that when the valve
95 and cylinder-ports at one end register those
at the other end of the cylinder will not.

The cylinder-ports are several in number,
by preference, (see Fig. 2,) and steam passages
a' lead from them to the cylinder.

The exhaust-ports are opened and closed in
100 a well-known manner by the ends of the
valve.

I will now proceed to describe the means which I have devised for giving to the above valve the necessary motions.

E is a lever adapted to rock upon a fixed pivot, e. The lower arm of the lever is connected with the valve-stem D by a link, F, pivoted to the lever-arm at f, and having a ball-and-socket joint with the valve-stem at f'. The upper arm of the lever E is oscillated by the positive eccentric, (not shown,) which thus opens and closes the exhaust-ports.

My principal improvements in the devices by which the oscillation of the valve is effected consist in certain universal-joint connections by which such oscillation is caused with much ease and accuracy, and also in an arrangement by which the oscillation of the lever E, which reciprocates the valve, is utilized to give a very desirable acceleration to its rotary cut-off action. The particular arrangement shown for causing this co-operation of the reciprocating with the rotating mechanism consists of a bell-crank lever, G, pivoted at g upon the lower arm of the lever E, an eccentric-rod, H, an eccentric, (not shown,) and a device for converting the oscillation of the bell-crank lever into an oscillation of the valve-stem in a plane at right angles to that of the former oscillation. The most convenient means for such conversion is a rod, J, connected by a ball-and-socket joint, j, with the arm g' of bell-lever G, and by a ball-and-socket joint, j', with a crank-arm, D', on the valve-stem. A rack-and-pinion movement or equivalent device might, however, be substituted.

The operation of this last-described mechanism is as follows: Supposing the positive eccentric-rod and the upper end of the lever E to be moving in the direction of the arrow 1, and the lower end of said lever and the valve-stem to be moving in that of arrow 2. Under such conditions the other eccentric (by its arrangement on the engine-shaft) and the lower end, g', of the bell-lever will be moving in the direction of the arrow 3, and the other arm, g', the rod J, and the crank-arm D' in the direction of arrows 4, to effect the cut-off of steam. It will now be evident that since the pivot g is being carried to the right by the lever E, while the lower arm of lever G is carried to the left by its eccentric, there will be an upward movement of the arm g' and a rotation of the valve-stem D in acceleration of or beyond the effect of the eccentric which operates the rod H. This gives a full steam-opening for a longer time and a more sudden cut-off.

The regulator of the engine is applied to the eccentric, which operates rod H. This may be of the character shown by my Patent No. 318,663, dated May 26, 1885.

It may be observed that if the lever G be pivoted to the lever E at such distance from the pivot of the latter as to receive sufficient bodily motion it would suffice to oscillate the valve if the rod H were connected to a fixed point. In such case the regulation might be effected by connecting the rod H, instead of

with a fixed point, with an ordinary ball-governor.

The rod J is arranged and constructed to be adjusted in length to properly regulate the valve.

I do not in this application claim that which is the subject-matter of my application Serial No. 188,014, and such matter of that application as is shown herein I hereby reserve to be claimed in that application.

Having thus described my invention, what I claim, and desire to secure by Letters Patent of the United States, is—

1. The combination, with a steam-chest or valve-easing having a steam-entrance port or ports, a, independent of the exhaust-port communicating with each end of the cylinder, and exhaust-ports as described, of a valve-stem and valve carried thereby, said valve being provided with transverse end partitions and with a port or ports, d, at each end, adapted to register alternately with or to be cut off from the ports a by the rotation of the valve, and thereby place the cylinder in communication with the live-steam duct, substantially as set forth.

2. The combination, with a steam-chest or valve-easing having a steam-entrance port or ports, a, independent of the exhaust-port communicating with each end of the cylinder, and exhaust-ports, as described, of a valve-stem and hollow cylindrical valve carried thereby, said valve being provided with transverse end partitions, with an opening for receiving live steam into its interior, and with a port or ports, d, at each end, adapted to register alternately with or to be cut off from the first-mentioned ports by the rotation of the valve, substantially as set forth.

3. The combination, with a rotating and reciprocating valve, of a rock-lever connected therewith to reciprocate the same, a bell-crank lever pivoted upon the rock-lever, means for oscillating said bell-lever relative to the rock-lever, and connections between the bell-crank lever and the valve for oscillating the latter, substantially as described.

4. The combination, with a rotating and reciprocating valve, of a moving part for reciprocating the valve, a bell-crank lever mounted upon a pivot carried by said part, means for oscillating the bell-crank lever relative to said moving parts, and connections between the bell-crank lever and the valve for oscillating the latter, substantially as set forth.

5. The combination of the valve and valve-stem, a rock-lever for reciprocating the same, the bell-lever G, arm D', and rod J, universally jointed, as described, for oscillating the valve, and the link F, pivoted to said rock-lever and having the universal joint f', with the valve-stem, substantially as set forth.

6. The combination, with a rotating and reciprocating valve, of a rock-lever connected therewith to oscillate the same, a bell-crank lever pivoted thereon, a speed-governor connected with said bell-lever for regulating its

motion relative to the rock-lever, and connections between the bell-crank lever and the valve for oscillating the latter, substantially as set forth.

5. 7. The combination, with a steam-chest or valve-casing having exhaust-ports, of the valve-stem D, and the hollow operating portions D' D'', for opening and closing the exhaust-ports by reciprocation, said portions being provided with ports which act by the oscillation of the valve, and the steam-chest be-

ing provided with the inlet b, communicating with the interiors of the said portions D' D'', and with cylinder-ports corresponding to the ports of said portions, substantially as set forth. 15

In testimony whereof I affix my signature in the presence of two witnesses.

FRANCIS SCHUMANN.
